Specification for Design.

Patented Feb. 22, 1921.

Application filed December 30, 1918. Serial No. 268,995. Term of patent 14 years.

To all whom it may concern:

Be it known that we, HENRY T. ATKINSON and BALDWIN VALE, both citizens of the United States, residing, respectively, at Oakland, in the county of Alameda and the city of San Francisco, State of California, have jointly invented a new, original, and ornamental Design for Toy Vehicles, of which the following is a specification, reference being had to the accompanying drawing, forming part thereof.

The figure is a side elevation of a toy vehicle, showing our new design.

We claim—

The ornamental design for a toy vehicle as shown.

In testimony whereof, we have hereunto set our hands at San Francisco, California, this 30th day of November, 1918.

HENRY T. ATKINSON.
BALDWIN VALE.

In presence of—

LINCOLN V. JOHNSON.
